US00D809589S

(12) **United States Design Patent** (10) Patent No.: **US D809,589 S**
Chatterton et al. (45) Date of Patent: ** Feb. 6, 2018

(54) **PORTABLE USER DEVICE**

- (71) Applicant: **PAYPAL, INC.**, San Jose, CA (US)
- (72) Inventors: **Geoffrey W. Chatterton**, Santa Clara, CA (US); **Akshay Sanjeevaiah Krishnaiah**, San Jose, CA (US); **Guhan Senguttuvan**, San Jose, CA (US); **Gunabalan Babu**, Fremont, CA (US); **Carlos Manuel Rivas**, Redwood City, CA (US); **Satish Narayan Govindarajan**, Los Altos, CA (US)
- (73) Assignee: **PAYPAL, INC.**, San Jose, CA (US)
- (**) Term: **15 Years**
- (21) Appl. No.: **29/567,177**
- (22) Filed: **Jun. 6, 2016**

Primary Examiner — Susan Bennett Hattan*Assistant Examiner* — Marie D. Fast Horse*(74) Attorney, Agent, or Firm* — Haynes & Boone, LLP**CLAIM**

The ornamental design for a portable user device, as shown and described.

DESCRIPTION

FIG. 1 is a front-bottom-right perspective view of a portable user device embodying the new design;

FIG. 2 is a rear-bottom-left perspective view thereof;

FIG. 3 is a rear-top-right perspective view thereof;

FIG. 4 is a front view thereof;

FIG. 5 is a right side view thereof;

FIG. 6 is a rear view thereof;

FIG. 7 is a left side view thereof;

FIG. 8 is a top view thereof; and,

FIG. 9 is a bottom view thereof.

The broken lines in the figures are provided for the purpose of illustrating portions of the portable user device form no part of the claimed design.
